UNITED STATES PATENT OFFICE.

WILLIAM R. BUSHBY, OF PUEBLO, COLORADO.

ORE-SEPARATOR.

SPECIFICATION forming part of Letters Patent No. 585,552, dated June 29, 1897.

Application filed July 31, 1896. Serial No. 601,229. (No model.)

To all whom it may concern:

Be it known that I, WILLIAM R. BUSHBY, a citizen of the United States, residing at Pueblo, in the county of Pueblo and State of Colorado, have invented a new and useful 5 Ore-Separator, of which the following is a specification.

My invention relates to mechanism for separating ores and precious metals or minerals; 10 and it has for its object to provide means for utilizing the relative specific gravities of the materials to be separated when whirled or exposed to centrifugal force, whereby said materials are stratified, and in connection 15 with such mechanism to provide means for adjusting the parts, whereby the degree of completeness of the separation may be varied.

Further objects and advantages of this invention will appear in the following description, 20 and the novel features thereof will be particularly pointed out in the appended claims.

In the drawings, Figure 1 is a vertical central section of an ore-separating machine constructed in accordance with my invention. 25 Fig. 2 is a similar view at right angles to the plane of Fig. 1. Fig. 3 is a plan view, partly in section, of the same. Fig. 4 is a detail transverse section of the scrapers and funnels and the contiguous portion of the centrifugal 30 receptacle or bowl on line 4 4 of Fig. 1. Fig. 5 is a similar sectional view of the refuse scraper and funnel on the line 5 5 of Fig. 1. Fig. 6 is a detail view in perspective of the adjusting-plate for regulating the position of 35 the scrapers and funnels. Fig. 7 shows in diagram different forms of edges for the dividing or separating blade, which is employed to pass between the strata of "savings" and "tailings."

40 Similar numerals of reference indicate corresponding parts in all the figures of the drawings.

1 designates a base or pedestal in which is mounted a driving-shaft 2, provided with a 45 pulley 3, and to the upper extremity of the shaft, which projects above the contiguous end of the pedestal, is attached a centrifugal receptacle or bowl 4, which in the construction illustrated is of inverted conical shape 50 with a contracted or trunco-conical upper end or mouth 5, formed by an overhanging flange or lip.

Supported by the pedestal and forming a skeleton frame around the receptacle or bowl are lateral braces 6, connected at their upper 55 ends above the upper extremity of the receptacle or bowl by a cross-bar 7 and a rear brace 8, between the upper end of which and an intermediate point of the cross-bar is mounted a tilting or rock bar 9, the extremities of which are reduced, as shown at 10, to fit in bearings, respectively, in the brace 8 and the bar 7.

The cross-bar supports a feeding-hopper 11, of which the neck portion 12 is engaged by a 65 stirrup or clip 13, provided with nuts 14, said neck portion of the hopper being located coaxially with the centrifugal receptacle or bowl.

In operation the ground or comminuted ore 70 is fed by the hopper into the rapidly-whirling receptacle or bowl, the same being deposited at the bottom or reduced end thereof when the receptacle or bowl is arranged in the upright position illustrated in the drawings, and 75 the centrifugal force causes the ore to climb the side walls of the receptacle or bowl. As the contents of the receptacle approach the point of largest diameter it becomes stratified by reason of the difference of the specific gravities of the different materials, those particles 80 which contain minerals or precious metals or the savings and which are of greater specific gravity being arranged in contact with the surface of the receptacle or bowl, while the 85 refuse or tailings forms a layer within the savings.

In order to concentrate the savings and tailings separately, I employ scrapers and funnels arranged with their operative edges at different 90 distances from the axis of rotation, one being at such a distance as to pass between the tailings and savings and direct the former into a suitable conductor, while the other is arranged contiguous to the surface of the receptacle or bowl to receive the savings. In 95 the construction illustrated the scrapers are in a main flared funnel 15, which communicates with a refuse or tailings conveyer 16, and a secondary funnel 17, which communicates 100 with a savings-conveyer 18, the outer wall 19 of the secondary or savings funnel having a reduced edge adapted to traverse or operate contiguous to the inner surface of the

receptacle or bowl at its point of greatest diameter and the main funnel being provided with a similar dividing knife or wall 20, which is preferably adjustable toward and from the 5 fixed wall or knife 19 of the secondary or savings funnel, whereby the relative positions of the walls or knives may be changed to suit the thickness of the stratum of savings, the thickness of this stratum being regulated by 10 the richness of the ore.

The means shown in the drawings for accomplishing the adjustment of the wall or knife 20 with relation to the fixed wall or knife 19 include a set-screw 21, arranged in 15 a slot 22 of the main funnel and engaging a transverse portion or ear 23 of the adjustable wall or knife.

The funnels are preferably flared laterally or in a direction perpendicular to the plane of 20 the flange 5 as well as radially or perpendicular to the plane of the side walls of the receptacle or bowl, whereby the adjoining edges of the funnels are respectively parallel with the contiguous angularly-disposed portions of the 25 inner surface of the receptacle or bowl.

The proximity of the edges of the funnels to the surfaces of the contiguous portions of the receptacle or bowl is regulated by means arranged in connection with the conveyers 16 30 and 18, which pass through openings 24 and 25, provided for their reception in the rock-bar 9, and in which they are secured by means of set-screws 26. Beyond this rock-bar the conveyers are engaged by a securing-plate 27, 35 also perforated to receive said conveyers and provided with a slot 28, engaged by a set-screw 29.

It is obvious that by loosening the set-screw the securing-plate may be adjusted parallel 40 with the axis of the receptacle or bowl to arrange the funnels of the scraping devices at any desired distance from the surface of the receptacle.

Obviously the dividing edge of the adjustable wall or blade 20 may be varied in shape 45 to suit different conditions of operation which may be found to be necessary in practice, and in Fig. 7 I have shown diagrams of different forms of cutting edges arranged in operative 50 relation with the contiguous portion of the receptacle or bowl. It will be seen by reference to said diagrams that I do not deem it necessary to arrange the edge of this dividing or separating blade 20 parallel with the 55 contiguous portion of the wall of the receptacle or bowl, but that the same may be arranged across the angle or may be of angular or curved construction.

Various changes in the form, proportion, 60 and the minor details of construction may be resorted to without departing from the spirit or sacrificing any of the advantages of this invention.

While in the drawings I have shown a considerable shoulder formed by the ear 23 of the 65 scraper 20, it will be understood that in practice this surface may be considerably re-

duced in area, and if found to obstruct the reception of the ore the same may be avoided by inclining it rearwardly or in the direction 70 of movement of the ore, this construction not being illustrated, however, for the reason that it will not materially affect the operation or the relative positions of the parts as shown and described.

Having described my invention, what I claim is—

1. An ore-separator having a centrifugal receptacle or bowl of inverted conical construction, and a plurality of conveyers, having a 80 common mouth arranged contiguous to the wall of the receptacle and provided with a plurality of scrapers corresponding in number with the conveyers, substantially as specified.

2. An ore-separator having a centrifugal receptacle or bowl of inverted conical construction, a plurality of conveyers having a common flared mouth, one edge of which forms a scraper to direct material into one conveyer, 90 and an intermediate partition in the mouth forming a scraper to deflect material into another conveyer, substantially as specified.

3. An ore-separator having a centrifugal receptacle or bowl, independent conveyers, a 95 common mouth for said conveyers having funnels or compartments communicating respectively with the conveyers, scraping-blades arranged at different distances from the axis of rotation of the receptacle to deflect different 100 strata of material into the funnels or compartments of the mouth, and means for varying the relative positions of said blades to suit the thickness of different strata, substantially as specified.

4. An ore-separator having a centrifugal receptacle or bowl of inverted conical construction and provided at its point of greatest diameter with an upwardly and inwardly inclined flange, main and secondary funnels of 110 cross-sectionally-angular construction communicating respectively with conveyers and having flared sides arranged respectively at an angle corresponding with that between the intersecting surfaces of the receptacle and 115 flange, and an intermediate dividing or separating blade arranged between the funnels to separate contiguous strata of material, substantially as specified.

5. An ore-separator having a centrifugal receptacle or bowl, contiguous funnels communicating with independent conveyers, fixed and movable scraping-blades arranged in operative relation respectively with said funnels at different distances from the wall of the receptacle, to direct different strata of materials into the funnels, and means for securing the movable blade at the desired interval from the fixed blade to suit the thickness of the exterior stratum, substantially as specified.

6. An ore-separator having an inverted conical centrifugal receptacle or bowl provided at its top with an upwardly-contracted flange, a rock-bar, funnels having scraping-blades

arranged at different distances from the axis of rotation, conveyers arranged in communication respectively with and carrying said funnels and supported by the rock-bar, whereby the rock-bar may be adjusted to vary the intervals between said blades and the wall of the receptacle, and means including a slotted securing-plate and a set-screw engaging the slot, for locking the funnels at the desired adjustment, substantially as specified.

7. An ore-separator having an inverted conical centrifugal receptacle, a plurality of conveyers having contiguous funnels and scraping-blades to deflect different strata of mate-

rial into the conveyers, a common rocking support for the conveyers, whereby they may be simultaneously adjusted, with the funnels and blades, to vary the intervals between the blades and the wall of the receptacle, and means for securing said support at the desired adjustment, substantially as specified.

In testimony that I claim the foregoing as my own I have hereto affixed my signature in the presence of two witnesses.

WILLIAM R. BUSHBY.
